[57] CLAIM

The ornamental design for an integrally formed insulator assembly, as shown and described.

DESCRIPTION

FIG. 1 is a left side elevational view of an integrally formed insulator assembly showing my new design;

FIG. 2 is a right side elevational view thereof;

FIG. 3 is a top plan view thereof;

FIG. 4 is a bottom plan view thereof;

FIG. 5 is an end elevational view thereof, the opposite end being a mirror image;

FIG. 6 is a sectional view taken along line V—V of FIG. 1;

FIG. 7 is a sectional view taken along line VI—VI of FIG. 1;

FIG. 8 is a fragmentary perspective view thereof;

FIG. 9 is a sectional view of one of the insulators as it would appear after crimping.

The electric terminal and wire are shown in broken lines for illustrative purposes only.
